UNITED STATES PATENT OFFICE.

DAVID S. RALSTON, OF CHICAGO, ILLINOIS, ASSIGNOR TO ALLIED PACKERS, INC., OF CHICAGO, ILLINOIS, A CORPORATION OF DELAWARE.

CONTAINER FOR HAMS AND THE LIKE.

Application filed June 10, 1926. Serial No. 114,906.

This invention pertains to packing house equipment such as is used in the re-shaping of hams, and is particularly concerned with a container of the type disclosed in the co-pending application of Joseph H. Appleton, Serial No. 89,538.

The object of the invention is to provide an improved container of the type described which is easy to apply to a ham, and is constructed in such a way that the complementary sections of the same are retained in fixed relation to each other either when open or closed.

While the foregoing statement is indicative in a general way of the nature of the invention, other objects and advantages will be apparent to those skilled in the art upon a full understanding of the container construction.

20 In order that the invention may be readily understood, one form of the same is presented herein, but it will of course be understood that such form is intended merely for the purpose of exemplification, and is not 25 to be considered as restricting the spirit of the invention short of its true and intended scope, as defined in the appended claims.

In the accompanying drawings—

Fig. 1 is a top view of the container when 30 open;

Fig. 2 is an end view when open;

Fig. 3 is a top view when closed;

Fig. 4 is an end view when closed; and

35 Figs. 5 and 6 are comparative views, showing a ham before and after being re-shaped in the container.

The container illustrated is of tubular form, and is composed of two generally semi-cylindrical sections 10 and 11 which are 40 hinged together by means of a rod 12.

The section 10 of the container consists of a large number of stiff wire ribs 13 which extend circumferentially of the container in spaced relation to each other and are looped 45 at corresponding ends around the hinging rod 12. The looped ends of the ribs 13 are maintained in fixed relation to each other by means of a reinforcing rod 14 which is welded or soldered to the outer surfaces of the 50 ribs adjacent the rod 12, and the intermediate portions of the ribs are also maintained in such relation by means of a larger rod 15 which is secured in a similar manner to the ribs. The free ends of the ribs 13 are 55 curved less than those portions of the ribs be-

tween the rods 14 and 15 and are reversely bent to form hooks 16 for a purpose herein-after described.

The section 11 likewise consists of a large number of stiff wire ribs 17 which extend circumferentially of the container and are looped at corresponding ends around the rod 12 at points intermediate the looped ends of the ribs of the section 10. The looped ends of the ribs 17 are maintained in fixed relation to each other by a reinforcing rod 18, and the free ends and intermediate portions of the ribs are also maintained in such relation by means of two larger rods 19 and 20.

The ribs 17 of the section 11 are of less 70 length than the ribs 13 of the section 10, and the free hooked ends of the ribs 13 project through the rectangular openings which are formed in the free edge of the section 11 by the arrangement of the rods 19 and 20 with 75 the ends of the ribs 17. When the container is in its open position, with the sections 10 and 11 swung apart as far as possible, the hooks 16 formed on the free ends of the ribs of the section 10 engage with the rod 19 and 80 prevent further separation between the lapped ribs of the sections, as shown in Fig. 2, and, when the container is closed, with the sections swung together to the extent necessary to produce a tubular jacket of the desired cross-sectional area, the free hooked ends of the ribs of the section 10 project 85 further through the rectangular openings in the section 11 and beyond the rod 20 of that section, as shown in Fig. 4.

The container construction above described permits the sections 10 and 11 to be swung easily into open or closed positions, and maintains the ends of the ribs of the sections in alternating relation regardless of 90 the extent to which the free hooked ends of the ribs of the section 10 may be bent toward or away from each other by the hard usage to which containers of this type are ordinarily subjected.

The container, after being closed about a ham or other piece of meat in a suitable press, may be held securely in its closed position by two or more adjustable latching devices 105 21. Each of the devices 21 consists of an operating lever 22 which is pivoted to the rod 15 of the section 10, and a hook 23 which is pivoted at 24 to the lever 22 and is provided at its free end with a number of notches 25 for hooked engagement with the 110

rod 19 of the section 11, the particular notch used being determined by the extent to which the container has been closed by the press. After the hook 21 has been swung over into engagement with the rod 19, the lever 22 is swung in the opposite direction until the point of connection 24 between the hook and the lever has passed beyond a dead center position relative to the centers of the rods 15 and 19, in which position the latching device will not open irrespective of the force exerted thereon through the rods 15 and 19.

After the container has been closed and latched about a ham or other piece of meat, the container with the ham therein may be conveniently suspended in the smoke house by means of a hook 26 which is formed from an extension of the hinging rod 12.

I claim:

- 20 1. A container of the character described, consisting of two hinged sections, each of which is composed of a plurality of circumferentially extending wire ribs which lap opposite the hinging axis with the ribs of the other section when the container is either open or closed.
- 25 2. A container of the character described, consisting of two hinged sections, each of which is composed of a plurality of circumferentially extending wire ribs which lap opposite the hinging axis with the ribs of the other section, and means for limiting the extent to which the sections may be opened with the ribs in lapped relation.
- 30 3. A container of the character described, consisting of two hinged sections, each of which is composed of a plurality of circumferentially extending wire ribs which lap opposite the hinging axis with the ribs of the other section, and hooks formed on the

ends of certain of the ribs for limiting the extent to which the container may be opened with the ribs in lapped relation.

4. A container of the character described, consisting of a longitudinally extending hinge rod, a plurality of wire ribs pivoted at corresponding ends to the rod with alternate ribs extending circumferentially from the same in one direction and intermediate ribs extending circumferentially in the opposite direction, a longitudinally extending reinforcing rod connected with one set of ribs adjacent the free ends thereof, and a plurality of hooks formed on the free ends of the other set of ribs for engagement with the reinforcing rod when the container is fully opened.

5. A container of the character described, consisting of a longitudinally extending hinge rod, a plurality of alternately long and short wire ribs pivoted at corresponding ends to the rod with the long ribs extending circumferentially from the same in one direction and the short ribs extending circumferentially in the opposite direction into lapped relation with the ends of the long ribs, a longitudinally extending reinforcing rod connected with the short ribs adjacent the free ends thereof, another longitudinally extending reinforcing rod connected with the short ribs adjacent the first mentioned reinforcing rod but on the opposite side of the ends of the long ribs, and a plurality of hooks formed on the free ends of the long ribs for engagement with the first mentioned reinforcing rod when the container is fully opened.

In testimony whereof I have hereunto subscribed my name.

DAVID S. RALSTON.
